UNITED STATES PATENT OFFICE.

JOSEPH JAMES FOLEY, OF CHICAGO, ILLINOIS.

DESIGN FOR AN AUTOMOBILE-DOOR.

58,734.

Specification for Design.

Patented Aug. 30, 1921.

Application filed March 14, 1921. Serial No. 452,332. Term of patent 14 years.

To all whom it may concern:

Be it known that I, JOSEPH JAMES FOLEY, a citizen of the United States, residing at Chicago, in the county of Cook and State of Illinois, have invented a certain new, original, and ornamental Design for an Automobile-Door, of which the following is a specification, reference being had to the accompanying drawing, forming a part thereof.

Figure 1 is a perspective view of an automobile door showing my new design; and

Fig. 2 is a sectional view on the line 2—2

of Fig. 1, this view being made to show the outside contour.

The portion 10 may be of glass, the frame 11 may be of aluminum, and the portion 12 may be a fabric having the appearance of leather.

I claim:

The ornamental design for an automobile door substantially as shown and described.

JOSEPH JAMES FOLEY.
